UNITED STATES PATENT OFFICE.

JOHN B. BAXTER, OF WATERVLIET, NEW YORK, ASSIGNOR TO COVERT MANUFACTURING CO., OF WATERVLIET, NEW YORK, A CORPORATION OF NEW YORK.

SNAP-HOOK.

1,276,010.

Specification of Letters Patent. Patented Aug. 20, 1918.

Application filed May 16, 1917. Serial No. 169,090.

To all whom it may concern:

Be it known that I, JOHN B. BAXTER, citizen of the United States, residing at Watervliet, in the county of Albany and State of New York, have invented certain new and useful Improvements in Snap-Hooks, of which the following is a specification, reference being had therein to the accompanying drawing.

10 This invention relates to improvements in hooks of that general type disclosed in my applications for Letters Patent, executed of even date herewith and specially designated case "A" and case "B," respectively.

15 The present improvements include an improved type of bar associated with the eye of the hook shank for relatively permanently closing said eye to prevent the escape of an inserted link, ring, or equivalent device to which it is desired that the hook be fastened.

20 The characteristics of the device reside in the special interfitting of the closure bar with the main eye portion, and also with the shank portion, to reinforce the bar against such strains as might tend to impair or dislodge the same, and that might be exerted against the bar from any direction. The details in the construction and arrangement of the several parts of the preferred embodiment of the present improvements will be apparent from the specific description hereinafter contained when read in connection with the accompanying drawings 35 forming part hereof, and wherein said embodiment is illustrated.

In the drawings,

Figure 1 is a face view of the device.

Fig. 2 is an edge view; and,

40 Figs. 3 and 4 are respectively transverse and longitudinal sectional views.

45 Referring more specifically to the drawings, wherein like reference letters refer to the same parts in the several views, A represents the shank provided with the usual snap hook B. At the opposite end of the shank, that is the end to constitute the attaching eye, I cast with the shank a hook-like eye member C, the end of which terminates in line with one side of the shank to dispose the eye D in a position approximately centrally of the longitudinal axis of the shank.

50 In line with the terminal portion of the

hook-like member and radially of the shank 55 the same is formed with an outwardly projecting flange E of considerable length to provide adjoining bearing shoulders or walls F at the opposite sides of the flange. The flange is perforated as at G for a purpose 60 as will later appear.

To close the space between the end of the hook-like portion of the eye and the end of the shank following the insertion of the ring, chain link, or its equivalent, adapted 65 to carry the hook, I utilize a bar H of an approximate size to constitute a substantial continuation of the hook-like member, said bar at that end which immediately adjoins the end of the hook-like member being 70 formed, at one face of the device with a projecting lug J adapted to be received within a pocket K in the corresponding face of the hook-like member to the end that the side edges of the lug will engage the side walls 75 of the pocket and tend to prevent movement of the closure bar in both lateral directions toward and from the eye D.

The other end of the bar from that just discussed is grooved as at L to receive and 80 inclose the flange on the shank to which I have previously alluded, the inner elongated edges of the walls of the slotted portion of the bar at opposite sides of said flange constituting abutting surfaces M to 85 contact with the corresponding surfaces or shoulders on the shank. The walls of the slotted portion of the bar are also pierced to present aligned apertures N designed to 90 register with the aperture in the flange of the shank for the reception of a locking pin O headed at one end as shown and provided with a cotter pin or equivalent device P at 95 its protruding end to effectually secure the parts together.

As the interfitting lug and pocket engagement reinforces the one end of the closure bar against movement toward and from the eye, so the locking pin and edge wall and shoulder engagement between the other end 100 of the bar and the shank will similarly reinforce this end of the bar. In addition to this, the slotting or equivalent bifurcating of the end of the bar so that its opposite walls embrace the opposite sides of the flange on the shank, is of advantage in offering resistance to forces or strains coming in contact with the bar facewise thereof 105

as distinguished from the edgewise resistance offered by the contacting edges and notch and pocket engagement referred to.

While I have herein disclosed one specific embodiment of the present invention it will be understood by persons skilled in the art that said invention is capable of embodiment in other forms and devices. For example, while the end of the bolt which is secured to the shank is slotted to provide a closed outer edge wall Q to enable the complete confining of the flange on the shank, on occasions this connecting wall may be omitted to provide a true bifurcation of this end of the bar, but this matter, once pointed out, being obvious, it will be unnecessary to specially illustrate.

Having thus described the invention, what I claim is:

1. A device of the character described comprising a hook carried by a shank, and means for closing the space between the end of the hook and the shank including a separate bar adjoining at one end the end of the hook and having an elongated portion at its opposite end overlying the shank, in combination with detachable means for removably securing adjacent portions of the bar and shank together to prevent relative movement thereof in any direction.

2. A device of the character described comprising a hook carried by a shank, and means for closing the space between the end of the hook and the shank comprising a bar adjoining at one end thereof the end of the hook and provided with an elongated recess in its opposite end, an elongated lug on the shank entering said recess, and means for securing the recessed portion of the bar and lug on the shank together, the securing means and relation of the recessed portion of the bar and shank being such as to prevent relative movement of the bar and shank in any direction.

3. A device of the character described comprising a hook carried by a shank, and means for closing the space between the end of the hook and the shank comprising a bar adjoining at its opposite ends the end of the hook and a part of the shank, and means for fixedly securing the bar in place against movement in any direction but permitting the bar to be moved intact from the hooked shank to open the eye of the hook.

In testimony whereof I hereunto affix my signature in the presence of two witnesses.

JOHN B. BAXTER.
